CLAIM

The ornamental design for a timepiece, as shown and described.

DESCRIPTION

FIG. 1 is a bottom and right-front perspective view of a timepiece showing my new design;

FIG. 2 is a front elevational view of FIG. 1;

FIG. 3 is a rear elevational view of FIG. 1;

FIG. 4 is a right-side elevational view of FIG. 1;

FIG. 5 is a left-side elevational view of FIG. 1;

FIG. 6 is a top plan view of FIG. 1;

FIG. 7 is a bottom plan view of FIG. 1;

FIG. 8 is a bottom and right-front perspective view of another embodiment of my new design of FIGS. 1-7;

FIG. 9 is a front elevational view of FIG. 7;

FIG. 10 is a rear elevational view of FIG. 7;

FIG. 11 is a right-side elevational view of FIG. 7;

FIG. 12 is a left-side elevational view of FIG. 7;

FIG. 13 is a top plan view of FIG. 7; and,

FIG. 14 is a bottom plan view of FIG. 7.

The broken-line showings of anterior portions of the watch are environmental only and form no part of the claimed design.
